CAR ROOF

William D. Thompson, Birmingham, Mich., assignor to Chicago-Hutchins Corporation, a corporation of Delaware

Application May 18, 1936, Serial No. 80,457

6 Claims. (Cl. 108—5.4)

The invention relates to metallic car roofs of the type known as two-plane roofs in which separate carlines are dispensed with and the roof is trussed by portions of the sheets lying in spaced planes. The present application forms a continuation in part of my former application Serial No. 760,006, filed December 31, 1934. With certain constructions of this type, the portions of the roof lying in the two planes are spaced from each other the greatest distance at the ridge or center of the roof and approach each other towards the eaves. Also, adjacent to the eaves the two planes are merged into a single plane which turns downward for attachment to the side plate of the car frame. A point of weakness in such structure is where the spaced planes merge into a single plane and various constructions have been devised for reinforcement at such point. It is the object of the present invention to obtain a construction which avoids this weakness and at the same time improves and cheapens the construction of the car by lowering the side walls thereof without loss in loading capacity, and the invention, therefore, consists in the construction as hereinafter set forth.

In the drawing:

Figure 1 is a cross-section through a car roof of my improved construction;

Figure 2 is a longitudinal section through a portion thereof;

Figure 3 is a perspective view of the reinforcing member between the roofing sheets and side plate of the car;

Figure 4 is an elevation viewed from the inside showing a plurality of units assembled into a single structure for shipment.

My improved roof is formed of a series of units each comprising an upper plane central portion A and lower plane opposite side portions B and B' which are connected to the upper plane portions by substantially vertical portions C. The portions B and B' are each preferably of somewhat greater than half the width of the portion A and these portions B and B' in adjacent units are connected to each other by welding. To provide for this and also to form a further reinforcement, the marginal portions of B and B' are upwardly offset as indicated at D, terminating in down-turned flanges E which are welded to each other. Thus, the offset portion D not only reinforces the structure but also facilitates welding and permits of making the lower plane panel of slightly greater width than the upper plane panel, while maintaining an equal degree of rigidity therein.

As previously described, the two planes are

spaced the greatest distance apart at the center and approach each other towards the eaves. Adjacent to the eaves both plane portions are curved downward and finally merge into a single plane which is attached to the side plane of the car. With my improved construction I make this curved portion of a larger radius than heretofore used, carrying the extensions of both upper and lower plane portions around the curve and substantially into the vertical before merging these portions into a single plane. This produces a lateral trussing effect, as well as that in the vertical plane, and the larger radius curves permit of lowering the height of the side walls of the car. However, at the point of merger of the two planes into a single plane there would still be a weakness, which I avoid by a reinforcement of peculiar construction.

As specifically shown, the radius of curvature of the upper plane extension F is approximately ten inches in length and the radius of the lower plane extension G is slightly less, such as nine and eleven sixteenths inches, and having its center lowered by an inch and a quarter. This maintains the spacing of the two curves up to the point H, where the direction is substantially vertical. From this point the portion G slopes outward in a portion I into the vertical plane of a portion J which is a continuation of the portion F. A reinforcing strip K is then used, this together with the portion J being riveted or otherwise secured to an upwardly extending flange L of a Z-bar side plate L'. This reinforcing strip is preferably a fashioned bar which extends upward above the flange L to a point H fitting about the portions I and J and secured thereto, preferably by welding. The strip preferably tapers in cross-section in an upward direction so as to avoid too great rigidity near its upper edge which might result in localizing stresses in the roofing sheet at such point. Also, by thus tapering the section it is more easily fashioned and adds less weight to the structure. The strip may be further used for uniting a plurality of units into a larger section and adds rigidity thereto permitting of shipment without danger of distortion.

The construction as above described, maintains full loading capacity within the car, while the dropping in the height of the side walls saves in cost of construction thereof. The roof is also stronger to resist the stresses to which it is subjected, than the constructions heretofore used.

What I claim as my invention is:

1. In a car roof, a roofing unit having an upper plane portion and a lower plane portion con-

5 nected by an intermediate portion, said upper and lower plane portions tapering towards each other from the ridge to the eaves, large radius curved extensions of said upper and lower plane portions at the eaves continuing in spaced relation to substantially a vertical plane and then merging into a single plane, and a reinforcement for the single plane portion extending upward into the spaced plane portions and fashioned in conformity thereto.

10 2. In a car roof, a series of like units each comprising vertically spaced non-parallel portions extending from eaves to eaves and converging from ridge towards eaves, said portions being connected by intermediate portions and at the eaves having large radius curved extensions maintained in spaced relation until reaching an approximate vertical plane, said curved portions then merging into a common plane, a side plate 15 having an upwardly extending flange to which said single plane portion is attached, and a reinforcing strip intermediate said flange and single plane portion, said strip extending upward into the spaced portions and being fashioned to 20 conform thereto.

25 3. In a car roof, a series of like units each comprising vertically spaced non-parallel portions extending from eaves to eaves and converging from ridge towards eaves, said portions being connected by transversely extending intermediate portions and having at the eaves large radius curved extensions maintained in spaced relation until reaching an approximate vertical plane and then merging into a common plane 30 portion, and a reinforcing strip extending along the juncture between the common plane portion and spaced curved portions being fashioned to conform thereto and secured by welding.

35 4. In a car roof, a series of like units each comprising vertically spaced non-parallel portions extending from eaves to eaves and converging from ridge towards eaves, said portions being connected by transversely extending intermediate portions and having at the eaves large radius curved extensions maintained in spaced 40

5 relation until reaching an approximate vertical plane and there merging into a common plane portion, and a reinforcing strip extending along the juncture between the common plane portion and spaced curved portions being fashioned to conform thereto and secured by welding, said strip being tapered in cross-section towards its upper edge to avoid localization of stresses.

10 5. In a car roof, a series of like units each comprising vertically spaced non-parallel portions extending from eaves to eaves and converging from ridge towards eaves, said portions being connected by transversely extending intermediate portions and having at the eaves large radius curved extensions maintained in spaced 15 relation until reaching an approximate vertical plane and there merging into a common plane portion, and a reinforcing strip extending along the juncture between the common plane portion and spaced curved portions being fashioned to 20 conform thereto and secured by welding, said strip being tapered in cross-section towards its upper edge to avoid localization of stresses and being of a length to extend along a plurality of units to secure and reinforce the same in a single 25 section for shipment.

30 6. The combination with the side plates of a car body, of a roof mounted thereon composed of units each having an upper plane portion and a lower plane portion connected by an intermediate portion, said upper and lower plane portions tapering toward each other from ridge toward the eaves and said lower plane portion being located in a plane which would intersect the vertical plane of the side plate at a point considerably above the upper end of said side plate and spaced therefrom by a dimension at least equal to the vertical dimension of said side plate, and large radius curved extensions of said 35 upper and lower plane portions tangent thereto and continuing in spaced relation to substantially a vertical plane and then merging into a single plane.
